LOCK

Alexander S. Karczewski, North Chicago, Ill., assignor to The Yale & Towne Manufacturing Company, Stamford, Conn., a corporation of Connecticut

Application May 9, 1944, Serial No. 534,719

17 Claims. (Cl. 292—169)

This invention relates to a door lock of that class in which a latchbolt is retracted by an outside rollback and an inside rollback, the rollbacks being preferably rotatable by inside and outside knobs. In this type of lock, a push piece is usually employed for locking the outside rollback, preferably leaving the inside rollback free for rotation. Means are generally provided for retaining the push piece in its locking position, and the said push piece is moved to unlocking position upon retraction of the latchbolt by endwise push thereagainst, or by rotation of the inside rollback by the inside knob.

The invention of this application relates particularly to means whereby the push piece is controlled in its movement relatively to the lock and the outside rollback. The invention relates further to the means whereby the push piece is moved to unlocking position when the latchbolt is retracted.

While the control mechanism for the push piece forming the contribution in this application is described by me as applied to a lock of the general class I have indicated, those skilled in the art will appreciate that my invention may be applied to other types of locks. It is therefore important that my invention be not considered as limited to application to a lock of the class described. It is also important to consider that I use the term push piece in its generic sense, and that my invention is not limited to a push piece such as I prefer to use; and to be particularly described here.

A feature of my invention resides in the utilization of a spring pressing against the push piece of my invention at an angle to the direction of movement of the push piece, and with a portion of the spring movable with the push piece into its locking and unlocking positions, whereby the spring helps greatly in controlling the movement of the push piece. A still further feature of my invention resides in the utilization of the spring so pressing against the push piece, for urging the latchbolt into its projected position.

A further feature of the invention resides in the means whereby the push piece, while urged into its locking and unlocking positions by the spring pressing thereagainst, is yieldingly maintained in either its locking or unlocking position.

A still further feature of my invention resides in the means whereby the latchbolt, in either one of its two possible positions in the lock casing, moves the push piece from a locking to an unlocking position when said latchbolt is retracted.

Referring now to the drawing, Fig. 1 is a hori-

zontal section through the lock of my invention showing it applied to a door. Fig. 2 is a view of certain of the parts of Fig. 1, and illustrating the push piece in its rollback locking position. Fig. 3 is a section taken along lines 3—3 of Fig. 1. Fig. 4 is a section taken along lines 4—4 of Fig. 3. Fig. 5 is an exploded view of the parts of my lock.

Referring now more particularly to the drawing, it will be noted that my lock is housed within a casing 10 that may be mounted in a door 11, to the faces of which are applied an outside rose 12 and an inside rose 13. The outside rose supports an outer knob 14 equipped with a spindle 15 for rotating an outside rollback 16 in the casing 10. Mounted for rotation relatively to the inside rose 13, is a knob 17 secured to a spindle 18 for rotating an inside rollback 19 also in the casing 10. Those skilled in the art will appreciate that inside spindle 18 is secured to the outside spindle 15 against endwise separation in a manner old in the art, the spindles being nevertheless rotatable relatively one to the other.

Mounted for sliding movement within the casing 10 of my lock, is a latchbolt 20 best illustrated in Fig. 5. Latchbolt 20 is formed with a head 21 and a centrally bored tail portion 22, terminating in a plate 23. Extending from the plate 23 are wings 24 whose function will be presently indicated.

For retracting the latchbolt upon rotation of either of the rollbacks 16 and 19 I utilize what is termed a retractor 25, best illustrated in Fig. 5. Retractor 25 is urged to the position illustrated in Fig. 3 by a spring 26 that fits at its right end in Fig. 3 about an abutment 27 formed on the end of the casing 10. At its left end the spring 26 fits about a lug 28 that is part of the retractor 25. Struck up lugs 29 are formed on the retractor 25 and cooperate with shoulders 30 of the inside rollback 19 and shoulders 31 of the outside rollback 16. The lugs 29 are of course maintained against the shoulders 30 and 31 under pressure of the spring 26 as well shown in Fig. 3, and therefore act to centralize the rollbacks 16 and 19 as will be appreciated by those skilled in the art. Retraction of the retractor 25 by either of the rollbacks 16, 19 brings yoke 33 of the retractor against plate 23 of latchbolt 20 and retracts the latchbolt from its positions of Figs. 1, 2 and 3.

The outside rollback 16 protrudes beyond the inside rollback 19, as seen in Fig. 3 and is formed with a slot 35 for cooperation with a locking lug 36 of a push piece 37 best illustrated in Fig. 5. Push piece 37 is mounted in openings 38 and 39

of the casing 10 for sliding movement transversely to the casing. For operating the push piece 37 I utilize a push button 40 that is assembled to the push piece 37 by threading the push button 40 into a suitable bore of the push piece as is well understood by those skilled in the art. The push button 40 is prevented from rotation out of assembled relation to the push piece 37 through its engagement with the inside rose 13. The assembling of the push button to the push piece, as well as the relation of the push piece to the inside rose 13, is all well known in this art.

When the push piece is in its position of Fig. 1 relatively to the remaining mechanism, both the inside and outside rollbacks are freely rotatable. When the push piece is depressed to its position of Fig. 2, the locking lug 36 enters the slot 35 of the outside rollback 16 and locks that rollback against rotation. For retaining the push piece 37 in its position of Fig. 1, or in its locking position of Fig. 2, I utilize a lug 41 formed on the retractor 25 as illustrated in Fig. 5, and a triangular lug 42 on the push piece 37, also shown in Fig. 5. The manner in which the lugs 41 and 42 cooperate will be indicated presently.

The push piece 37 is formed with a lug 43 over which is placed the right hand end of a spring 44. The other end of the spring 44 is mounted within the bore 45 of the sleeve portion 22 of the latchbolt 20. It is obvious that the spring 44 effects the projection of the latchbolt 20. The spring 44 also acts to maintain the push piece yieldingly in either its locking or unlocking position through the utilization of the lugs 41 and 42 set forth in the preceding paragraph. Thus, it will be noted in Fig. 1 that the spring 44 is depressed out of its axial alignment, and that it therefore tends to maintain the push piece in the position of Fig. 1 with its triangular lug 42 below the lug 41 on the retractor. When the push piece is depressed, the spring is moved therewith to its position of Fig. 2, and assists in maintaining the triangular lug 42 above the lug 41 formed on the retractor.

It will of course be appreciated that when the push piece is moved from its position of Fig. 1 to the position of Fig. 2, it will actually momentarily move the retractor to the right through the camming action of the triangular lug 42 relatively to the lug 41. It will now be further appreciated that should the retractor be moved to the right in Fig. 2 through the rotation of inside knob 17, the lug 41 will be withdrawn from below triangular lug 42 on push piece 37. Simultaneously, one of the wings 24 of the latchbolt will abut the triangular lug 42 and move the pushpiece from its position of Fig. 2 to its position of Fig. 1. In other words, retraction of the latchbolt by the inside knob effects the movement of the push piece to its release position.

Should the push piece be in its position of Fig. 2 with the door open, and should the door be swung shut, the latchbolt 20 will be retracted due to the rearward camming action of the usual strike contacting the latchbolt head 21. One of the wings 24 will then contact the triangular lug 42 of the push piece 37 and will move the push piece to the position of Fig. 1 in exactly the same manner as indicated above. The retractor 25 will of course yieldingly resist this movement but its resistance is slight.

It is important to note that the two wings 24 on the latchbolt are formed to allow reversing of the latchbolt relatively to the lock mechanism. Thus, the latchbolt may be rotated 180° from its

position in Figs. 1, 2 and 3 without in any way affecting the operation of the mechanism. Those skilled in the art will fully appreciate the value of this feature.

I believe that the construction and operation of my invention will now be apparent to those skilled in the art.

I now claim:

1. In a lock of the class described, a casing, a push piece mounted for sliding linear movement on said casing, a helical spring pressing axially thereof at one end against said push piece transversely to the direction of sliding movement of said push piece, and against a part of the lock at its other end, and means whereby said push piece moves said end of the spring with it as it moves on said casing.

2. In a lock of the class described, a casing, a push piece mounted for movement on said casing, a helical spring positioned with its axis at right angles to said push piece and bearing at one end thereof against said push piece, and against a part of the lock at its other end, and means whereby said push piece moves said end of the spring to one or the other side of the axis of said spring as said push piece moves on said casing.

3. In a lock of the class described, a casing, a push piece means mounting said push piece for linear sliding movement on said casing between a locking and a releasing position, a helical spring pressing axially thereof at one end against said push piece substantially at right angles to the direction of sliding movement of said push piece, and against a part of the lock at its other end, and means whereby said push piece moves the end of the spring with it as it moves on said casing between said positions whereby said spring presses against said push piece at one or the other side of the axis of said spring when said push piece is in one or the other of said positions.

4. In a lock of the class described, a casing, a push piece mounted for sliding movement on said casing between a locking and a releasing position, a spring pressing axially thereof at one end against said push piece substantially perpendicularly to the direction of movement of said push piece and against a part of the lock at its other end, and means whereby said push piece moves the end of the spring with it as it moves on said casing between said positions whereby said spring presses against said push piece at one or the other side of the axis of said spring when said push piece is in one or the other of said positions.

5. In a lock of the class described, a casing, a latchbolt slidable longitudinally of said casing, a rollback for retracting said latchbolt, a push piece for locking said rollback movable on said casing between locking and unlocking positions relatively to said rollback, a spring positioned longitudinally of said casing and effecting at its outer end the urging of the latchbolt to a projected position, the inner end of said spring bearing against the said push piece and moving with the said push piece as said push piece moves relatively to said casing.

6. In a lock of the class described, a casing, a latchbolt slidable longitudinally of said casing, a rollback for retracting said latchbolt, a push piece for locking said rollback slidable transversely of said casing between locking and unlocking positions relatively to said rollback, a helically wound spring positioned with its axis longitudinal of said casing and effecting at its

outer end the urging of the latchbolt to a projected position, the inner end of said spring bearing against said push piece and maintained by said push piece out of its normal axial alignment when said push piece is in either its locking or its unlocking positions.

7. In a lock of the class described, a casing, a push piece mounted for movement on said casing between locking and releasing positions, a spring pressing axially thereof at one end against said push piece and against a part of the lock at its other end, means whereby said push piece moves the end of the spring with it substantially perpendicularly to the axis of said spring as said push piece moves on said casing between said positions, and detent means yieldingly retaining said push piece in each of said positions.

8. In a lock of the class described, a casing, a push piece mounted for sliding movement on said casing between a locking and a releasing position, a spring pressing axially thereof at one end against said push piece substantially perpendicularly to the direction of movement of said push piece and against a part of the lock at its other end, means whereby said push piece moves the end of the spring with it as it moves on said casing between said positions, and detent means yieldingly retaining said push piece in each of said positions.

9. In a lock of the class described, a casing, a latchbolt slidable longitudinally of said casing, a rollback for retracting said latchbolt, a push piece for locking said rollback slidable transversely of said casing between locking and unlocking positions relatively to said rollback, a spring positioned longitudinally of said casing and effecting at its outer end the urging of the latchbolt to a projected position, the inner end of said spring bearing against the said push piece and moving with the said push piece transversely of said casing, and detent means yieldingly retaining said push piece in each of said positions.

10. In a lock of the class described, a casing, a latchbolt slidable longitudinally of said casing, a rollback for retracting said latchbolt, a push piece for locking said rollback slidable transversely of said casing between locking and unlocking positions relatively to said rollback, a helically wound spring positioned with its axis longitudinal of said casing and effecting at its outer end the urging of the latchbolt to a projected position, the inner end of said spring bearing against said push piece and maintained by said push piece out of its normal axial alignment when said push piece is in either of its positions, and detent means yieldingly retaining said push piece in each of said positions.

11. In a lock of the class described, a casing, a latchbolt slidable longitudinally in said casing, inside and outside rollbacks for retracting said latchbolt, a retractor through which said rollbacks retract said latchbolt, a spring pressing said retractor into a position corresponding to the projected position of said latchbolt, a push piece slidable transversely of said casing into locking and unlocking positions, means whereby said push piece when in locking position locks the outside rollback while leaving the inside rollback unlocked, a spring positioned longitudinally of said casing and effecting at its outer end the urging of the latchbolt to a projected position, the inner end of said spring bearing against the said push piece and moving with the said push piece transversely of said casing, and detent means on said

retractor for yieldingly retaining said push piece in each of said positions.

12. In a lock of the class described, a casing, a latchbolt slidable longitudinally in said casing, inside and outside rollbacks for retracting said latchbolt, a retractor through which said rollbacks retract said latchbolt, a spring pressing said retractor into a position corresponding to the projected position of said latchbolt, a push piece slidable transversely of said casing into locking and unlocking positions, means whereby said push piece when in locking position locks the outside rollback while leaving the inside rollback unlocked, a spring positioned longitudinally of said casing and effecting at its outer end the urging of the latchbolt to a projected position, the inner end of said spring bearing against the said push piece and moving with said push piece transversely of said casing, detent means on said retractor for yieldingly retaining said push piece in each of said positions, and means on said latchbolt for moving said push piece from its locking position to its unlocking position when said latchbolt is retracted.

13. In a lock of the class described, a casing, a latchbolt slidable longitudinally in said casing, inside and outside rollbacks for retracting said latchbolt, a retractor through which said rollbacks retract said latchbolt, a spring pressing said retractor into a position corresponding to the projected position of said latchbolt, a push piece slidable transversely of said casing into locking and unlocking positions, means whereby said push piece when in locking position locks the outside rollback while leaving the inside rollback unlocked, a spring positioned longitudinally of said casing and effecting at its outer end the urging of the latchbolt to a projected position, the inner end of said spring bearing against the said push piece, means whereby said spring moves with the said push piece transversely of said casing, detent means on said retractor for yieldingly retaining said push piece in each of said positions, said latchbolt being adapted for reversal through insertion in said casing in rotated positions 180° apart, and means on said latchbolt in each of said rotated positions adapted to move said push piece from its locking position to its unlocking position when said latchbolt is retracted.

14. In a lock of the class described, a casing, a latchbolt movable in said casing, a rollback for retracting said latchbolt, a push piece for locking said rollback movable on said casing between locking and unlocking positions, said latchbolt being adapted for reversal through insertion in said casing in rotated positions 180° apart, and means on said latchbolt in each of said rotated positions adapted to move said push piece from its locking position to its unlocking position when said latchbolt is retracted.

15. In a lock of the class described, a casing, a latchbolt slidable longitudinally of said casing, a rollback for retracting said latchbolt, a dog for locking said rollback movable in said casing between locking and unlocking positions, said latchbolt being adapted for reversal through insertion in said casing in rotated positions 180° apart, and means on said latchbolt in each of said rotated positions adapted to move said dog from its locking position to its unlocking position when said latchbolt is retracted.

16. In a lock of the class described, a casing, a latchbolt slidable longitudinally in said casing, a rollback for retracting said latchbolt, a push piece slidable transversely of said casing into lock-

ing and unlocking positions, means whereby said push piece when in locking position locks the rollback, detent means for yieldingly retaining said push piece in each of said positions, said latchbolt being adapted for reversal through insertion in said casing in rotated positions 180° apart, and means on said latchbolt in each of said rotated positions adapted to move said push piece from its rollback locking position to its unlocking position when said latchbolt is retracted.

17. In a lock of the class described, a casing, a latchbolt slideable longitudinally in said casing, inside and outside rollbacks for retracting said latchbolt, a retractor through which said rollbacks retract said latchbolt, a spring pressing said retractor into a position corresponding to the pro-

- jected position of said latchbolt, a push piece slideable transversely of said casing into locking and unlocking positions, means whereby said push piece when in locking position locks the outside rollback while leaving the inside rollback unlocked, a spring positioned longitudinally in said casing and bearing at its outer end against the latchbolt and at its inner end directly against said push piece, means whereby said push piece moves the inner end of said spring as said push piece moves from unlocking to locking position, detent means for yieldingly maintaining said push piece in either of said positions, and means whereby the retraction of said latchbolt moves said push piece from locking to unlocking position.

ALEXANDER S. KARCZEWSKI.
